UNITED STATES PATENT OFFICE.

CHARLES A. DREIER, OF CHICAGO, ILLINOIS.

WATER-CLOSET BEND.

No. 872,332.

Specification of Letters Patent.

Patented Dec. 3, 1907.

Application filed February 23, 1907. Serial No. 358,909.

To all whom it may concern:

Be it known that I, CHARLES A. DREIER, a citizen of the United States of America, and a resident of Chicago, county of Cook, State 5 of Illinois, have invented certain new and useful Improvements in Water-Closet Bends, of which the following is a specification.

This invention relates to plumbing, and its main objects are to provide an improved, 10 durable, and inexpensive form of water and gas-tight joint for pipes which are especially suited for the connection between water closet bends and the bowls thereof; and to provide a joint of this class which may be 15 readily adjusted through a considerable range to suit the different conditions which arise in different buildings. These objects are accomplished by the device shown in the accompanying drawings, in which:

20 Figure 1 is a section of a water closet bend constructed according to this invention. Fig. 2 is a top plan of the same.

The body part 1 of the bend is of a usual form having a hub 2 of usual form at the end 25 of its upper branch. This hub has an inner annular shoulder 3 at its lower end and has an enlarged interior adapted to receive the end of an adjoining pipe and permit of being filled with lead and calked in the usual manner. The bend 1 is connected by means of 30 an adjustable section of pipe or thimble, with the closet bowl, which is not shown in the drawings. This thimble is formed of two telescoping parts having threaded engagement with each other and permitting of adjusting the length of the thimble. The lower 35 end of the lower part or ring 4 is beaded similarly to the "spigot" end of a cast iron pipe and is adapted to be seated upon the shoulder 40 3 within the hub 2.

The upper part 5 of the thimble is internally threaded at its ends. The part 4 is so proportioned that the lower end of the upper part 5 of the thimble will extend inward of 45 the hub 2 in all positions of adjustment of said parts, thus insuring that when a filling of lead or other suitable material is calked into the space between the thimble and the hub, a perfectly gas-tight and water-tight 50 joint will be formed both between the thimble and the hub and between the two parts of the thimble. The thimble has a horizontally-disposed flange 6 at its upper end for connecting it to the closet bowl. This flange 55 is preferably provided with an externally threaded nipple which extends into the

thimble 5, the joint between the thimble and flange being rendered water and gas-tight by means of an interposed gasket 10. The purpose of the threaded joint between the thimble and flange is to permit the flange to be removed for the purpose of calking the joint between the hub 2 and the thimble. The flange 6 is grooved at 7 near the inner periphery of its upper face to provide a seat for a 60 65 gasket between said flange and the closet bowl.

In connecting up a closet by means of the bend which is herein described, the flange 6 is screwed into position on the thimble and the 70 parts of the thimble are then adjusted with respect to each other, so that the flange is in proper relation with the lower end of the closet bowl when the lower part 4 of the thimble rests upon the shoulder 3. The 75 flange 6 is then removed and the usual filling of oakum 8 and lead 9 is then placed into the space between the hub 2 and the thimble, being finally calked so as to make a permanent joint. The flange 6 is then screwed 80 back into position on the upper end of the thimble and is ready for connection with the closet bowl completed.

What I claim as my invention and desire to secure by Letters Patent is:

1. A pipe having a hub at one end, an annular shoulder located inward of said hub, a second pipe extending into said hub, and a ring having threaded engagement with said second pipe and adapted to bear on said 85 shoulder for adjusting said second pipe with respect to the first, said hub being suitably formed to permit sealing material to be filled into the space between said hub and second pipe for sealing the joint, substantially as described.

2. A pipe having a hub at one end, a thimble extending into said hub and having an adjustable joint for varying the length of the thimble, said joint being located inward of 100 the hub, said hub being suitably formed to provide a space around the thimble adapted to be filled with material for rendering airtight both the joint between said thimble and hub and the joint in said thimble.

3. A pipe having a hub at one end, a shoulder at the inner end of said hub, a thimble extending into said hub and resting upon said shoulder, said thimble being formed of two parts telescoping each other and adjustable with respect to each other for varying the length of the thimble, and said hub being

suitably formed to permit of filling the space between said hub and thimble for simultaneously sealing both the joint between said thimble and hub and the joint between the 5 parts of said thimble.

4. A pipe having a hub at one end, a shoulder at the inner end of said hub, a thimble extending into said hub and supported by said shoulder, said thimble comprising two 10 tubular parts having a screw-threaded joint located inward of the hub, and said hub being suitably formed to permit material to be filled between said thimble and the hub for sealing both the joint between the thimble 15 and hub and the joint between the parts of said thimble.
5. A pipe having a hub at one end, a thim-

ble extending into said hub and having an adjustable joint for varying the length of the thimble, said joint being located inward of 20 the hub, said hub being suitably formed to provide a space around the thimble adapted to be filled with material for rendering airtight both the joint between said thimble and hub and the joint in said thimble, and a 25 flange at the outer end of said thimble having screw-threaded engagement therewith.

Signed at Chicago this 19th day of February, 1907.

CHARLES A. DREIER.
